CATHETER

Floyd C. Hendrickson, Canton, Ohio

Application March 16, 1937, Serial No. 131,125

2 Claims. (Cl. 128—349)

This invention relates to catheters and similar tubular appliances for surgical or other uses, and has for its principal objects the provision of a superior catheter construction providing maximum interior diameter or cross-sectional area with minimum wall thickness and minimum outside diameter together with desirable transverse rigidity to resist collapse and also a certain amount of longitudinal rigidity, especially in the tip of the catheter, to facilitate insertion of the frequently rather long and slender catheter into a restricted tubular passage such as a male urethra, and generally to provide economy and efficiency in catheter constructions.

15 The manner in which these and other objects of the invention are attained will appear from the following description of the invention in which reference will be had to the accompanying drawing of which—

20 Fig. 1 is an elevation, partially broken away for clarity of illustration, showing a catheter embodying the principles of the present invention;

25 Fig. 2 is a sectional elevation, on an enlarged scale, illustrating more clearly constructional details of the tip portion of the catheter of Fig. 1.

Fig. 3 is a vertical section taken on line 3—3 of Fig. 1.

For purposes of illustration, I have shown my 30 invention in a preferred form embodied in a urethral catheter comprising a relatively long and slender thin-walled rubber tube 10 having a closed tip end 11 and an enlarged open end 12 adjacent which the rubber wall of the tube 10 is made considerably heavier for a short distance to provide a tube-gripping connector portion 13. Drainage openings 14, 14 are provided in the tube wall, preferably in diametrically opposed positions, adjacent the tip end 11 of the tube 10. 35 Embedded wholly within the wall of the thin-walled tubular portion of the catheter and extending substantially from the end of the tube-gripping connection portion 13 to a point a short distance from the drainage openings 14, 14, is provided a reenforcing coil 15 of, for example, 40 spring steel wire providing a high degree of transverse rigidity and effectively preventing collapse of the tube, which in prior devices often occurs as a result of bending or other collapsing pressure while in use, and also imparting to the catheter a considerable amount of longitudinal 45 rigidity without however destroying its flexibility.

50 For imparting greater longitudinal rigidity to the tip of the catheter into which the wire coil

15 does not extend and which is weakened considerably by the cut-out drainage apertures, a U shaped loop of wire 16 is embedded in the wall of the tip, with the rounded portion of the U circling the rounded tip of the catheter 5 and with the legs of the U extending back through the catheter wall preferably at least as far as the end of the wire coil 15 and desirably, although not necessarily, engaging the wire coil positively as by means of hooks 17 formed at 10 the ends of the two legs of the U.

To provide additional rigidity in the catheter tip, and especially to provide resistance to puncture by the sound or stylet customarily used for facilitating insertion of the catheter, the rubber 15 wall at the tip and adjacent areas, preferably at least as far as the end of the wire coil 15, may be made heavier and thicker as more clearly shown in Fig. 2, to provide a wall say about twice as thick as the wall of the tube proper. 20

For ordinary catheters, the coil wire reenforcing element 15 and the U shaped tip reenforcing element 16 may be formed of stainless steel wire of about 0.007 inch gauge, the coil 25 preferably having a low pitch, for example 20 coils to the inch. With such a reenforcing element, an overall catheter wall thickness of as low as 0.03 to 0.05 inch is regularly used and has been found to be entirely reliable and wholly satisfactory. Substantial advantages are noted 30 even with walls as thick as 0.10 inch. Such a slight wall thickness of course insures maximum fluid capacity within the catheter for any permissible outside diameter, or from a different point of view, permits substantial reduction in 35 the outside diameter of the catheter with lessened pain and discomfort to the patient, but without reduction of fluid capacity. Considerable variation in the character and dimensions 40 of the reenforcing elements and in the overall wall thickness of course are contemplated in catheters for various uses. Whereas ordinary soft-rubber catheters having walls as thin as those of the present catheter would have practically no transverse rigidity, the catheter of the 45 present invention positively resists collapse while in use, even when doubled upon itself, but is nevertheless freely flexible for ready insertion through tortuous body passages, such insertion being greatly facilitated by the substantial longitudinal stiffness of the catheter, and especially by the reinforced tip.

The integral tube-gripping connector portion 13 permits convenient coupling of the catheter 55

to other tubes or apparatus when it is desirable to do so.

The "rubber" embodied in the catheters of the present invention may be caoutchouc, gutta percha, balata, or similar natural or synthetic more less rubbery materials including such synthetic materials as plasticized polymerized vinyl chloride, polymerized chloroprene known as neoprene, and the like, but preferably is unmasticated latex rubber deposited directly from natural rubber latex which of course may be suitably pre-conditioned for use according to known processes. Such unmasticated latex rubber is especially resistant to the repeated sterilizations to which a surgical appliance must be subjected, is sufficiently tough and strong to withstand rough usage, and, more particularly, is well adapted to form a cohesive coating completely embedding and firmly holding the metallic wire reinforcing elements utilized in the present invention.

Numerous modifications and variations may be made in the invention as herein described without departing from the spirit and scope of the discovery as defined by the appended claims.

I claim:

1. A catheter or similar appliance comprising a relatively long and slender tubular portion having a relatively thin rubber wall, a closed tip thereon having a relatively thicker rubber wall provided with a transverse aperture, a helical wire reinforcing element embedded within the relatively thin wall of the tubular portion and extending through a substantial length of said tubular portion and providing transverse rigidity therefor, the successive convolutions of the helical reinforcing element being definitely spaced apart, and a U shaped wire reinforcing element embedded within the relatively heavier wall of the tip providing longitudinal rigidity therefor, all of said rubber being unmasticated latex rubber having the properties of rubber deposited directly from rubber latex.

2. A catheter or similar appliance as defined in claim 1 in which the legs of the U shaped reinforcing element extend to and are positively engaged with the helical wire reinforcing element.

FLOYD C. HENDRICKSON. 25
